JOSEPHINE L. HOLT AND WILLIAM N. HOLT, OF OAKLAND, CALIFORNIA

ABDOMINAL SUPPORT

Application filed December 18, 1929. Serial No. 414,897.

The invention is for an abdominal support.

The main object of the invention is to provide a form fitting abdominal support in which the body material is knitted to the approximate desired contour of the abdomen of the wearer.

Another object of the invention is to provide a support as before described, which, in addition to vertical side adjusters, is also provided with an inelastic adjustment at the lower horizontal edge of the device, for providing a cupping form for support of the lower part of the abdomen.

Another object of the invention is to provide a device of the class described, which may readily be attached to the carrier member or corset, and as readily detached or replaced.

Another object of the invention is to provide means for anchorage of a bust retainer, on said device for the purpose of retaining said bust retainer in desirable and comfortable position.

Another object of the invention is to provide a device of the class described which will be comfortable, effective, and of neat appearance, and which may be adjusted to suit changing conditions of form of the wearer.

Other objects of the invention will become apparent from the drawings, and as the description is set forth, as also from the appended claims.

Referring to the accompanying drawings:

Figure 1 is a perspective view of the improved abdominal support showing the front panel in open position;

Figure 2 is a horizontal sectional view taken through Fig. 1 on line 2-2;

Figure 3 is a front elevational view of the improved abdominal support per se, inserts and laces removed;

Figure 4 is a vertical sectional view taken on line 4-4 of Fig. 3.

Similar reference characters are used to designate similar parts throughout the several views.

The corset or carrier member comprises back panels 10 and 11 which are adaptable to be fitted to the back of the wearer when prop-

erly adjusted by means of laces 12 cooperating with eyelets 13 at the contiguous edges of members 10 and 11. Tapes of eyelets 14 vertically disposed, are attached to the corset members 10 and 11 adjacent their opposite edges, preferably two tapes being provided on each member, thus providing additional adjustment for the abdominal support. Garters 15 are attached to members 10 and 11 for support of the stockings of the wearer.

The front panel 16 consists of an ornamental fabric, provided with a reinforcing fabric 17 indicated dotted, and having attached thereto, garters 15. The opposite vertical edges of panel 16 are provided with hooks 18, adapted to cooperate with eyelets in tapes 14. The panel 16 is intended to be folded over the abdominal support to conceal said support and provide a neat appearance to the wearer. Shoulder straps 19 and 20 attached to members 10 and 11, as indicated at 21 and 22, the opposite edges being attached to front panel 16 as indicated at 23 and 24, are provided to retain the upper edges of the corset in proper position.

The abdominal support per se 25 consists of the two form knitted members 26 and 27, which are so formed, in knitting by known means, as to cup under and conform to the contour of a protruding abdomen. A firm cord is used in knitting the members, and due to the members being knitted, a slightly yieldable fabric is thereby provided which lends itself somewhat to the conformation of the abdomen. Members 26 and 27 are preferably supplied at their contiguous vertical edges with cooperating fastening means 43 of any desired known make, such as zippers or hooks and eyes. Stays 28 are inserted in retaining casings attached to members 26 and 27, and may consist of the well-known steels or whale bone, to provide a uniform contour to the device and retain the upper edge 29 in relative position to lower edge 30 against the weight of the abdomen. Hooks 31 are provided adjacent the upper edge to cooperate with eyelets on a bust retainer, when one is worn, and are intended to retain the bust retainer in proper and comfortable relation. The lower edges of members 26 and 27 are

folded outwardly over and upward, being formed into hems 32^a and 32 for slidably receiving adjusting inelastic tapes 33 and 34, which tapes are attached to members 26 and 27, as indicated at 35, and being free to slide within the hems 32^a and 32, the ends passing out through open ends of hems 32^a and 32 at their contiguous edges, thence coincidentally cooperating with a slide buckle, adapted to 10 receive the ends of both tapes, thus providing means for accentuating the cup form of the lower part of the support per se by adjustment of the tapes 33 and 34 in buckle 36. The outer vertical edges 37 and 38 are provided 15 with eyelets 39 adapted to receive the customary corset laces. Inserts 40 are provided with eyelets 41 adapted to receive laces 42 at one vertical edge thereof, said laces 42 providing adjustment of the support per se 20 longitudinally, the opposite edges of inserts 40 being provided with hooks adapted to cooperate with the eyelets in tapes 14.

It will be noted that the support per se may be readily attached to any corset by attaching 25 to said corset tapes of eyelets as indicated at 14, and that the abdominal support may be removed by releasing the fastening means 43, and that the entire support may be detached from the corset by releasing the hooks 30 18 cooperating with eyelets on tapes 14, that additional adjustment can be secured by means of the plurality of tapes 14, and that the lower portion of the support may be adjusted independently of the balance of the 35 support.

Having thus set forth the advantages of the invention and described an operative method of construction and use, what we claim is:

40. 1. In combination with a corset provided with one or more vertically disposed tapes of fasteners adjacent each inseam, an abdomen support, comprising a pair of body members, vertically disposed stays on said body members, hems adjacent the lower edges and adapted to receive a pair of tapes, said tapes being attached at their outer edges to said body members, said tapes being slidable in said hems and protruding therefrom at the 45 contiguous edges of said body members, means for retaining said tapes in adjusted position, inserts adapted to be detachably attached to said corset by means of said fasteners, and laces cooperating between said 50 body members and said inserts for adjusting said support.

2. In combination, corset back panels adjustably secured along their vertical edges by means of laces and cooperating eyelets, 55 stays incorporated in said panels, the opposite edges of said panels being provided with one or more rows of eyelets, a front panel member having hooks disposed on its opposite vertical edges and adapted to cooperate 60 with the eyelets on said back panels, a reen-

forcing member in said front panel, garters attached to the lower portion of said front and back panels, an abdominal support comprising a pair of form knitted body members, fastening means at the contiguous vertical edges of said body members, stays vertically disposed and attached to said body members, outwardly and upwardly turned hems at the lower edge of said body members, said hems adapted to slidably receive adjusting cords or tapes therein, said tapes being attached to said body members at their farther ends, a buckle slidably receiving and retaining said tapes in adjusted position at their contiguous ends, eyelets adjacent the opposite vertical edges of said body members, inserts having disposed at one edge thereof eyelets, laces cooperating with said eyelets on said inserts and said body members, the opposite edges of said inserts being provided with hooks adapted to attach said abdomen support to the cooperating eyelets on said back panels.

3. An abdominal support comprising a corset having inseams and provided with fastening means adjacent the inseams, an abdomen support composed of a yieldable form knitted fabric, centrally disposed vertical fastening means, stays vertically disposed and retained in casings attached to said fabric, adjusting means at the lower edge of said support, adjusting means vertically disposed at both sides thereof, fastening means cooperating with said fastening means on said corset, and means adjacent the upper edge of said abdomen support for cooperation with retention means for a bust supporter.

4. In combination, an abdominal support comprising a form-knitted body and detachable inserts, vertically disposed adjusting means adjacent both sides of said support cooperating with said detachable inserts and said body, inelastic adjusting means at the bottom thereof for cupping said support, said detachable inserts being adapted for attaching said support to a corset or similar structure.

5. In combination, an abdominal support comprising a body of form knitted fabric and detachable inserts, vertically disposed adjusting means adjacent the sides of said support cooperating with said detachable inserts, inelastic adjusting means at the lower edge thereof for producing a cup effect for retention of the abdomen, said detachable inserts being adapted for attaching said support to a corset or similar device, and means for securing a bust retainer to the upper edge of said support.

6. In combination, an abdominal support comprising a body of form knitted fabric, stays vertically disposed thereon, vertically disposed adjusting means on both sides thereof, detachable inserts cooperating with said adjusting means, inelastic flexible ad-

justing means cooperating with the lower edge of said body, and means for attaching said combination to a corset or similar device by means of said inserts.

5 In testimony whereof we have affixed our signatures.
